GOLF BALL WASHER

Filed July 13, 1928

UNITED STATES PATENT OFFICE

EDWARD M. LAING, OF HIGHLAND PARK, ILLINOIS

GOLF-BALL WASHER

Application filed July 13, 1928. Serial No. 292,491.

This invention relates to a golf ball washer, and more particularly to an improved apparatus that may be located near a tee for expeditiously and efficiently cleaning a golf ball.

The principal object of the invention is to provide an improved means for reciprocating a golf ball between a pair of brushes immersed in a cleaning liquid such as water, this means being adapted to rotate the ball so as to expose different surfaces thereof to the brushes. In the specific form here disclosed, the ball-holder is provided with an elongated slot or opening in which the ball moves bodily from end to end of the slot at each change of the direction of reciprocation of the ball-holder. An inclined bar at one side of the opening provides a surface which engages one side of the ball, and on which the ball rolls during this movement from end to end of the slot, so as to rotate the ball about an axis inclined at an acute angle to the path of bodily movement of the ball, so as to bring new faces of the ball into engagement with the brushes.

Another object is to provide improved means for adjusting the brushes toward or from the ball-holding member.

Other objects and advantages of this invention will be more apparent from the following detailed description of one approved form of the apparatus.

In the accompanying drawings:

Fig. 1 is a transverse vertical section 35 through the apparatus, the view being taken substantially on the line 1—1 of Fig. 2.

Fig. 2 is a longitudinal vertical section taken substantially on the line 2—2 of Fig. 1.

Figs. 3 and 4 are similar views, showing 40 the ball-holder and ball in different positions from that shown in Fig. 2.

Fig. 5 is a transverse section through the ball-holder, the view being taken substantially on the line 5—5 of Fig. 4.

45 The supporting standard, of any suitable

form, comprises an upright post 1 having an outstanding collar or flange 2 below the cylindrical upper end 3 on which is rotatably mounted the collar 4.

The horizontal cover plate 5 of the golf ball washer is formed at one side with an upstanding vertical flange 6 which is secured by bolts 7 to the supporting collar 4. The cover plate 5 is formed with a longitudinally extending central slot 8, and at either side of this slot are upstanding flanges or brackets 9 and 10, the bracket 10 being connected with flange 6 by the strengthening web 11.

A lever 12 is provided at an intermediate point with a pivot opening 13, by means of which it is fulcrumed on the shaft 14 journaled in the flanges or brackets 9 and 10. A pair of cover flaps 15, adapted to normally close the slot 8, have ears 16 pivoted on shaft 14 at either side of the lever 12. The longer upper arm 17 of lever 12 is formed as an operating handle which may be oscillated back and forth through an arc of substantially 180° above the horizontal plane of the top of plate 5. During this movement the shorter lower arm 18 of lever 12 will project downwardly through slot 8 in cover plate 5, and be oscillated therebeneath.

A pair of similar brushes or other equivalent scrubbing devices are mounted in opposed positions beneath the plate 5, the backs 19 of the brushes being secured to the bottom of plate 5 by screws 20 which pass through slots 21 elongated transversely of the plate 5. The slots 21 permit the brushes to be adjusted toward or from one another. The bristles 22 of the brushes project toward one another so that the space therebetween is less than the diameter of the golf ball. The lower end 18 of the lever 12 is adapted 55 to oscillate between these brushes.

An open topped receptacle 23 for holding the water or other cleaning liquid is suspended beneath cover plate 5 in any suitable manner. As here shown, laterally project-

ing ears 24 on plate 5 are received between pairs of similar ears on receptacle 23, and pins 25 passed through these ears serve to support the receptacle 23. A downwardly projecting flange 26 on the lower face of plate 5 fits within receptacle 23 and holds the receptacle in properly centered position.

The lower end of arm 18 of lever 12 is expanded into the form of a loop 27 which ¹⁰ closes an elongated opening 28, this opening being of slightly greater width than the diameter of a golf ball and of considerably greater length, so that the golf ball may have a substantially bodily movement from end ¹⁵ to end of this slot or opening 28. The longitudinal axis of the elongated opening 28 extends at an acute angle to the longitudinal center line of lever 12, and consequently at an acute angle to the path of movement of the ball between the brushes 22. It will be noted that the lever 12, and the loop 27 for holding the ball, are of substantially less thickness than the diameter of the golf ball so that the ball will project at either side of the loop ²⁵ into engagement with the bristles 22 of the brushes. An integral cross-bar 29 extends diagonally of the elongated opening 28 at one side of the loop 27 so that as the ball moves from one end to the other of the opening 28, one side thereof will roll along the cross bar. Since the cross bar 29 extends at an acute angle to the path of bodily movement of the ball along said opening, a rolling movement will be imparted to the ball by this ³⁰ bar about an axis also positioned at an angle to the length of the elongated opening 28. This will continually cause new portions of the ball to be exposed to the brushes 22.

When the handle 17 is swung down to the ⁴⁰ right to the dotted line position shown in Fig. 2, the ball-holding loop 27 will be elevated out of the receptacle 23 to the dotted line position, carrying one of the flaps 15 upwardly with it, so that a ball 30 may be inserted within the opening 28. The handle 17 is then ⁴⁵ swung upwardly and oscillated back and forth so as to oscillate the lower end 18 of the lever and the ball-holder 27 between the brushes 22. As the lever 17 is first swung in the direction of the arrow *a* (Fig. 2) and the ball-holding loop 27 is moved in the direction of the arrow *b*, the ball 30, as soon as it has ⁵⁰ engaged the brushes 22, will be moved to the rear end of slot or opening 28 in the direction of the arrow *c*, moving from the dotted line position to the position shown in full lines in Fig. 2. The ball will remain in this position until the end of this stroke of the lever, at which time the ball and ball-holder will ⁵⁵ be in substantially the positions shown in Fig. 4. When the opposite stroke of the lever starts, in the direction of the arrow *d* (Fig. 3), the ball, which is retarded by its engagement with the brushes, will be moved bodily ⁶⁰ to the upper end of opening 28 in the direc-

tion of the arrow *e*, until it reaches the position shown in Fig. 3. During this bodily movement of the ball lengthwise of slot or opening 28, one side of the ball will engage with and roll along the transverse bar 29 so that, as already described, new faces of the ball, will be exposed to the brushes. At the next change of direction of the lever, the ball will again move to the other end of the slot, in the direction indicated by the arrow *c* (Fig. 2) again rolling along the cross-bar 29 to expose new faces of the ball to the brushes. ⁷⁰

The pivoted flaps 15 normally close the slot 8 so as to prevent splashing during the cleaning operation, and to prevent evaporation of the cleaning liquid when the device is not in use. These flaps are automatically lifted by the ball-holder when it is swung out of the receptacle at either side, and close automatically by their own weight. ⁷⁵

By simply removing the pins 25, the receptacle 23 may be removed to clean the same or to renew the supply of liquid therein. ⁸⁰

It will be noted that the entire assembly is carried by the collar 4 at the upper end of post 1 so that the washer may be conveniently swung to any position about the post. In a copending application, Serial No. 289,835, filed July 2, 1928, I have shown a reservoir for an additional supply of cleaning liquid, ⁹⁰ this reservoir also being carried by the collar 4, but at the opposite side of the post from receptacle 23 and provided with means for automatically replenishing the liquid supply within receptacle 23. In said copending application this reservoir is shown in connection with a somewhat different form of golf ball washer, but it is to be understood that the reservoir is equally adapted for use with the present preferred form of the washer. ⁹⁵

It will be noted that as the ball 30 moves from end to end of the slot 28, which is inclined to the arcuate path of travel of the ball, it will engage new portions of the brushes. In this way all of the wear does not fall ¹⁰⁰ along a single path in the brushes and the effective life of the brushes is increased. ¹⁰⁵

While water will ordinarily be sufficient as a cleaning agent, it is to be understood that other cleaning fluids may be used in this apparatus. Also other means than brushes might be used as scrubbing agents, for example, pads of felt or similar material. In the following claims, the term "brushes" is intended to cover all such equivalent devices. ¹¹⁵

I claim:

1. A golf ball cleaner comprising a receptacle for holding liquid, a pair of opposed brushes mounted in the receptacle, a member mounted for reciprocation between the brushes, the member being of less thickness than the diameter of a golf ball and formed with an opening of sufficient size to permit the ball to move bodily therein, and means carried by the member and extending over the ¹²⁵ ¹³⁰

opening at one side thereof for engaging the ball and causing it to rotate about an axis inclined at an angle to the path of bodily movement of the ball as the ball moves from one side of the opening to the other.

5. 2. A golf ball cleaner comprising a receptacle for holding liquid, a pair of opposed brushes mounted in the receptacle, a member mounted for reciprocation between the brushes, the member being of less thickness than the diameter of a golf ball and formed with an elongated opening for receiving a golf ball, and a cross bar on said member positioned diagonally of the opening at one side thereof, the ball having a rolling engagement with the bar as it moves from one end of the opening to the other.

3. A golf ball cleaner comprising a receptacle for holding liquid, a pair of opposed brushes mounted in the receptacle, and a member pivoted intermediately above the receptacle and formed with an upper handle portion, and a lower portion of less thickness than the diameter of a golf ball and adapted to swing between the brushes, the member being formed with an opening in its lower portion for loosely receiving a golf ball and means carried by the member for engaging one side of the ball to cause it to rotate as the member is oscillated about its pivot.

4. A golf ball cleaner comprising a receptacle for holding liquid, a pair of opposed brushes mounted in the receptacle, and a member pivoted intermediately above the receptacle and formed with an upper handle portion, and a lower portion of less thickness than the diameter of a golf ball and adapted to swing between the brushes, the member being formed with an elongated opening in its lower portion for receiving a golf ball, and a cross bar on said member positioned diagonally of the opening at one side thereof, the ball having rolling engagement with the bar as it moves from one end of the opening to the other.

5. A golf ball cleaner comprising a receptacle for holding liquid, a closure for the receptacle having a central slot therein, a pair of opposed brushes mounted on the lower face of the closure at either side of the slot so as to project down into the receptacle, means for securing the brushes to the closure permitting adjustment of the brushes toward or from one another, and a member carried by the closure and projecting through the slot so as to move between the brushes, the lower portion of the member being formed to loosely carry a golf ball.

6. A golf ball cleaner comprising a receptacle for holding liquid, a closure for the receptacle having a relatively large longitudinal slot therein and a plurality of small transverse slots, a pair of opposed brushes carried beneath the closure and projecting down into the receptacle, securing means passing

down through the transverse slots and engaging the brushes to support same from the closure so that they may be adjusted toward or from one another, and a member intermediately pivoted on the closure and projecting down through the longitudinal slot so that the lower end thereof will swing between the brushes, this member being of less thickness than a golf ball and formed with an opening for loosely receiving the ball.
